HYDRAULIC SERVOMOTOR

Lawrence Farnell Mott, Walton, Stone, England,
assignor to H. M. Hobson Limited, London,
England, a company of Great Britain

Application May 27, 1950, Serial No. 164,760
In Great Britain June 10, 1949

5 Claims. (Cl. 121—41)

1

Hydraulic servomotors are normally fitted with a control valve which is movable in opposite directions from a neutral position to effect alternative pressure and exhaust connections to opposite sides of the motor, thereby causing the motor to move an output member in a direction, and to an extent, determined by the movement imparted to an input member linked to the control valve.

Where a servomotor of this kind is employed for positioning the control surface of an aircraft, serious danger can arise in the event of a control valve seizing in an open position, and thereby causing the pressure to drive the control surface to an undesired extreme position.

U. S. application, Serial No. 164,654, now Patent No. 2,597,418, discloses mechanism for safeguarding against this contingency, embodying a collapsible member which, when the control valve seizes, collapses and thereby actuates mechanism for rendering the servomotor inoperative and permitting manual control of the output member.

This invention approaches the problem of valve seizure on different lines, and provides a hydraulic servomotor embodying duplicated control parts, namely a normally operative control valve and an emergency control valve, which is movable, as the result of effort exerted on the input member when the normally operative control valve seizes, to take over control of the output member and permit of servo operation thereof from the input member.

With the control valve provided in accordance with the invention, therefore, the servomotor is not rendered inoperative, as in the above-mentioned cases, but can continue to work as a servomotor under the control of the emergency control valve.

In one form of servomotor according to the invention the normally operative control valve slides in a ported sleeve which is biased so that it is held stationary so long as the valve can move freely in it but is caused to move in relation to its housing, in the event of the valve seizing in the sleeve, and, when so moved, first reverses the pressure and exhaust connections established to the servomotor by the seized valve and thereafter permits of control of the servomotor, through the ports in the sleeve, in accordance with the control exerted over the input member.

In an alternative arrangement, the emergency control valve is disposed parallel to the normally operative control valve and linked to it and to

2

the input member, the emergency control valve being normally resiliently held against movement but being movable, if the other control valve seizes, first to reverse the pressure and exhaust connections to the servomotor established by the seized control valve and thereafter to take over control of the servomotor.

With the servomotor according to the invention irreversibility is maintained when the normally operative valve seizes and the emergency valve takes over from it. Also if the seized valve frees itself normal functioning is restored.

Two embodiments of the invention will now be described in detail, by way of example, with reference to the accompanying drawings, in which—

Fig. 1 is a diagram of the first form of servomotor, and

Fig. 2 is a diagram of the second form of servomotor.

Like reference characters designate like parts in the two figures.

The servomotor shown in Fig. 1 comprises a cylinder 3 movable in relation to a fixed piston 4 and carrying a valve housing 5. The piston rod 6 is attached, at 7, to a fixed structure and the cylinder is coupled to an output member 8. In the housing 5 is disposed a sleeve 9 within which is a slideable piston valve 10. The sleeve 9 is provided with centering springs 11, one at each end, which normally hold the sleeve in a central position and prevent the sleeve from moving when the piston valve 10 is moved axially in the sleeve 9 by a manually operable input member 12. Each spring 11 bears against a washer 13 which, in turn, bears against a retaining cover 14 secured to the housing 5 by screws 15. Secured to the ends of the sleeve 9 are collars 16 which bear against the washers 13.

Liquid under pressure is admitted to the housing through an inlet 17 communicating with a central inlet port 18 and two additional inlet ports 19 to the bore containing the sleeve, the additional inlet ports 19 being equally spaced at opposite sides of the central port 18 and normally masked by the sleeve 9, as shown. Liquid is returned to the source of supply from an outlet 20 which is connected to outlet ports 21 from the housing bore, these being outside, and spaced equally from, the respective additional inlet ports 19. The sleeve 9 has an inlet port 22 normally coincident with the central inlet port 18 in the housing and two outlet ports 23 normally coincident with the outlet ports 21 in the housing. Emergency ports 24 in the sleeve lie midway be-

tween each of the additional inlet ports 19 and the adjoining outlet port 21.

The ports 18, 19, 21, 22 and 23 are all of the same width w . The emergency ports 24 in the sleeve are each of width $2w$. The outer edge of each emergency port 24 in the sleeve is at a distance w from the inner edge of the adjoining outlet port 23 in the sleeve, the inner edge of each outlet port 21 is at a distance $4w$ from the outer edge of the adjoining additional inlet port 19 and the inner edge of each additional inlet port 19 is at a distance at least $3w$ from the adjoining edge of the central inlet port 18.

The piston valve 10 has two waisted sections 25 formed upon it between lands. The central land 26 has a width equal to or slightly greater than that of the inlet port 22 in the sleeve while the width of each waisted section 25 is equal to or slightly less than the distance between the adjacent edges of the associated inlet and outlet ports 22, 23 in the sleeve.

On the opposite side of the sleeve to that carrying the ports 22, 23, 24 are formed slots 27, each communicating with a port 28 formed in the housing. These ports 28 are of a width w and each is located midway between the inlet port 22 in the sleeve and one of the outlet ports 23 in the sleeve. The slots 27 are of width $5w$ and also are located midway between the inlet and outlet ports 22, 23 in the sleeve. The ports 28 connect with passages 29 which conduct liquid to and from opposite ends of the servo cylinder 3.

The sleeve 9 may be slid axially a distance of $2w$ in either direction from the central position by compression of one of the springs 11. Further movement is prevented by one or other of the washers 13 abutting against a surface 30 on the housing 5.

The piston valve 10 may be slid axially by an amount $2w$ in both directions relative to the housing, provided the sleeve 9 is in a central position, movement being limited by abutment of collars 31 formed on the piston valve against the retaining covers 14. If the sleeve 9 is displaced by some amount in one direction, the piston valve 10 may be displaced the full amount $2w$ in the same direction, but the collar 16 at the end of the sleeve 9 which projects from the housing will limit displacement of the piston valve 10 in the other direction to an amount equal to the difference between $2w$ and the sleeve displacement.

In normal operation the sleeve 9 remains stationary, and control of the servomotor is effected by movement of the piston valve 10. Displacement of it in either direction causes the central land 26 to uncover the inlet port 22 and admit liquid to one passage 29, while liquid returning along the other passage 29 passes to the outlet 20 by virtue of one of the end lands 32 of the valve uncovering the associated outlet port 23. Thus, if the valve 10 is moved to the left liquid is admitted from the inlet port 22 to the left hand end of the cylinder 3 and the right hand end of the cylinder 3 is connected to the left hand outlet port 23. Consequently the cylinder 3 moves to the left. As the cylinder moves, the housing 5 and sleeve 9 travel with it in the same direction as that in which the piston valve 10 was moved, the movement ceasing when the sleeve has caught up with the displaced piston valve, thereby closing the inlet port 22 and the open outlet port 23.

If the piston valve 10 seizes within the sleeve when displaced by any distance, say to the left as seen in Fig. 1, up to the maximum of $2w$, the 75

operator will resist undesired continued motion of the servomotor by applying force in the opposite direction to the displacement of the piston valve, which will cause the sleeve 9 with seized valve 10 therein to slide within the housing in the opposite direction to the displacement of the piston valve relative to the sleeve, i. e. to the right. When the sleeve has travelled a distance of w to the right, the inlet port 22 in the sleeve will no longer be open to the inlet port 18 in the housing thus cutting off the supply of liquid to the motor. Similarly the outlet ports 23 in the sleeve will no longer be aligned with the outlet ports 21 in the housing, thus also cutting off the flow of liquid leaving the motor. Further displacement of the sleeve 9 causes the left hand emergency port 24 to start to uncover the associated additional inlet port 19 in the housing, thus admitting pressure liquid to the left hand port 28 which was previously connected, by movement to the left of the piston valve 10, with the outlet 20, while the other emergency port 24 simultaneously starts to uncover the right hand outlet port 21 in the housing, permitting liquid to be exhausted from the other port 28, which was previously connected to the inlet 17. The direction of motion of the servomotor is thus reversed.

The motion of the servomotor in the reverse direction will cease when the housing 5, travelling to the right with the servomotor, overtakes the sleeve 9 and closes the ports 24 therein. The operator will thus retain control over the servomotor, with a small change in the datum position of the output member 3 in relation to the input member 12 occasioned by the displacement of the sleeve 9 in relation to the housing 5. If the piston valve 10 frees itself, the springs 11 will return the sleeve 9 to central position and the piston valve 10 will resume control.

Should the piston valve 10 seize in the sleeve 9 at the mid-position, when there is no flow to or from the motor, the sleeve 9 must be moved a distance w in either direction before the servomotor will commence to move in the corresponding direction.

In the alternative form of the invention shown in Fig. 2, the housing has formed within it two cylindrical bores in which slide two cylindrical piston valves 10, 40, the axes of which are substantially parallel. The piston valves 10, 40 are pivoted at their ends to a link 33 which is pivoted at an intermediate point 34 to the input member 12. The piston valve 40 is constrained from sliding axially by means of springs 11 bearing against washers 13 which in turn abut against covers 14 secured to the housing 5. Collars 16 formed on the piston valve 40 engage with the washers 13 and axial movement can occur only when the force applied to the piston valve 40 is sufficient to overcome the springs 11.

Liquid under pressure is admitted at the inlet 17 and conducted as before to an inlet port 18 and additional inlet ports 19 in the housing. Exhausted liquid returns to the source of supply from outlet 20 which is connected to outlet ports 21 and additional outlet ports 35 in the housing. Complementary to ports 18, 19, 35 and 21 are ports 36, 37, 38 and 39 respectively, communication between them being possible only when grooves 41, 42 and 43 in the valve 40 register with the ports.

The ports and grooves are disposed in a particular manner with regard to each other. In the mid-position ports 18 and 36 are aligned

with groove 41 and each pair of ports 21 and 39 is aligned with a groove 43.

All the ports and grooves have the same width w . Adjacent edges of each pair of ports 21 and 35 are about $2w$ apart, and adjacent edges of each pair of ports 19 and 18 are about $3w$ apart, while the adjacent edges of each pair of ports 19 and 35 are also $3w$ apart. Each groove 42 is located midway between one pair of ports 19 and 35.

The port 36 communicates with another port 44 opening into the bore of the piston valve 10 and normally masked by the central land 26 thereof. The ports 39 connect with corresponding ports 45 normally masked by the end lands 32 of the valve 10, while each pair of ports 31 and 38 connects via a common passage with a port 46 communicating with one of the waisted portions 25 of the valve 10.

In normal operation, the piston valve 40 is retained stationary by its springs 11 and movement of the input member 12 serves only to displace the piston valve 10. The land 26 then uncovers the port 44 and admits liquid under pressure to one of the passages 29 connected to the servo cylinder. Simultaneously one of the lands 32 uncovers its outlet port 45 and connects it to the other passage 29 to exhaust liquid from the servomotor to the outlet 20. Should the piston valve 10 seize within the housing 5 when displaced from the mid-position, e. g. to the left, the operator will resist undesired motion by application of force to the input member 12 causing a force to be applied to the piston valve 40 which, if sufficient to overcome the appropriate spring 11, will displace the piston valve 40 in the opposite direction, i. e. to the right. When piston valve 40 has moved a distance w to the right, the pressure supply to the port 44 is cut off and simultaneously exhaust liquid from the left hand port 45 is prevented from escaping, thus causing undesired motion to cease. Further movement to the right of the piston valve 40 will place the right hand ports 35 and 38 in communication via the right hand groove 42 and simultaneously the left hand ports 19 and 37 will be connected by the other groove 42, so that the flow of liquid to the servo cylinder is reversed in direction.

If the piston valve 10 seizes within the housing in the mid-position, with the land 26 covering the port 44, the piston valve 40 must be moved a distance w in each direction before the servomotor commences to move in the corresponding direction.

The piston valve 40 has a maximum permissible movement of $2w$ in each direction from the mid-position, while the piston valve 10 has a movement of w in either direction from the mid-position. Movement of the input member 12 relative to the housing 5 is limited by stops 50, coacting with a cover plate 51, to an amount which is so proportioned in relation to the point of connection of the input member 12 to the link 33 that the piston valve 10 may just travel the full amount w permitted by collars 31 on it. Application of force to the input member 12 can only move the piston valve 40 when the piston valve 10 is not free to slide within the limits permitted by its collars 31.

While in the examples which have just been described, the control valve serves to control pressure and exhaust connections to opposite ends of a servo cylinder, it will be appreciated that the control valve may, as an alternative, control pressure and exhaust connections to a

hydraulic motor, for example as described in the above mentioned Patent No. 2,597,418 so as to cause the hydraulic motor to position the output member in accordance with the position assumed by the input member.

What I claim as my invention and desire to secure by Letters Patent is:

1. In a hydraulic servomotor, a control valve assembly comprising a valve housing, a sliding piston valve, an input member coupled to the piston valve, a ported sleeve surrounding the valve and normally held by springs in a central position, in relation to the housing, pressure and exhaust connections to the housing, and a pair of outlets from the housing to the servomotor, the sleeve having a pair of normally operative ports through which, on sliding movement of the piston valve in the sleeve in either direction from a neutral position, alternative pressure and exhaust connections are established to the outlets according to the direction of movement of the piston valve and also a pair of emergency and normally inoperative ports, said sleeve being movable against its springs, in the event of valve seizure and by effort applied to the input member, in the direction opposite to that in which the piston valve has been displaced, to position to render said normally operative ports ineffective and to render said emergency ports effective to establish, in accordance with the direction of movement of the sleeve, alternative pressure and exhaust connections to the outlets.

2. In a hydraulic servomotor, a control valve assembly comprising a valve housing, an input member, a pair of parallel sliding piston valves mounted in said housing, a linkage connecting said valves together and to the input member, springs normally holding one of said valves against movement in relation to the housing, pressure and exhaust connections to the housing, passages in the housing, and a pair of outlets from the housing, said spring loaded valve having grooves through which, on sliding movement of the other valve in either direction from a neutral position, alternative pressure and exhaust connections are established through certain of said passages to the outlets according to the direction of movement of said valve and said spring loaded valve being movable against its springs, in the event of seizure of said other valve in said housing and by effort applied to the input member, in a direction opposite to the direction of displacement of the seized valve, to position to render said grooves ineffective and to render a pair of normally inoperative emergency grooves in the spring loaded valve effective to establish through other of said passages, in accordance with the direction of movement of said spring loaded valve, alternative pressure and exhaust connections to the outlets.

3. A hydraulic servomotor, comprising a servo member, a housing, a cavity in said housing accommodating said servo member, a pressure inlet to said housing, an exhaust outlet from said housing, an input member, a main control valve mounted to slide in said housing and connected to said input member, said main control valve normally constituting the sole controlling agency for the servomotor and being movable by said input member in opposite directions from a neutral position, passages in said housing controlled by said main control valve, said passages being closed when said main control valve is in its neutral position but effecting, on movement of said main control valve from its neutral posi-

tion, alternative connections between the inlet and outlet and the opposite ends of said cavity according to the direction of movement of said control valve, an emergency control valve operatively connected to said input member, said emergency control valve being movable in said housing in opposite directions from a neutral position, further passages in said housing controlled by said emergency control valve, said further passages being closed when said emergency control valve is in its neutral position but effecting, on movement of said emergency control valve from its neutral position, alternative connections between the inlet and outlet and opposite ends of said cavity, and means restraining said emergency control valve against movement from said neutral position, said restraining means yielding, in the event of seizure of the main control valve against movement relatively to said housing, to permit of displacement of said emergency control valve by said input member.

4. A hydraulic servomotor, comprising a servo member, a housing, a cavity in said housing accommodating said servo member, a pressure inlet to said housing, an exhaust outlet from said housing, an input member, a sleeve mounted to slide in said housing, biasing means normally restraining said sleeve against movement from a central position in said housing, a control valve coupled to the input member and mounted to slide in said sleeve, passages in said housing, and ports in said sleeve, said passages and ports serving, under control of said control valve, to establish alternative connections between the pressure inlet and the exhaust outlet and opposite ends of said cavity according to the direction of movement of said control valve from a neutral position, and said sleeve being movable by said input member, on seizure of said main control valve in said sleeve, to establish through said ports and passages alternative pressure and exhaust connections to said cavity and thereby to effect operation of the servomotor under control of said input member.

5. A hydraulic servomotor, comprising a servo member, a housing, a cavity in said housing accommodating said servo member, a pressure inlet to said housing, an exhaust outlet from said housing, an input member, a main control valve mounted to slide in said housing, connected to said input member and movable thereby in opposite directions from a neutral position, passages in said housing, said main control valve being effective when moved by said input member to establish through certain of said passages alternative connections between the pressure inlet and the exhaust outlet and opposite ends of said cavity according to the direction of movement of said main control valve from its neutral position, a normally inoperative emergency control valve mounted to slide in said housing, an operative connection between said emergency control valve and said input member, and resilient means for normally preventing movement of said emergency control valve by said input member, said resilient means yielding, in the event of seizure of said main control valve in said housing, to permit of movement of said emergency control valve by said input member and thereafter to establish through others of said passages alternative pressure and exhaust connections to said cavity permitting of operation of the servomotor by said input member.
